UNITED STATES PATENT OFFICE.

JAMES W. BROWN, OF MILWAUKEE, WISCONSIN, ASSIGNOR OF ONE-HALF
TO EDWARD T. NIQUET, OF MILWAUKEE, WISCONSIN.

HAT-FORMING BLOCK.

SPECIFICATION forming part of Letters Patent No. 732,163, dated June 30, 1903.

Application filed December 8, 1902. Serial No. 134,310. (No model.)

To all whom it may concern:

Be it known that I, JAMES W. BROWN, residing at Milwaukee, Milwaukee county, and State of Wisconsin, have invented a new and useful Improvement in Hat-Forming Blocks, of which the following is a description, reference being had to the accompanying drawings, which are a part of this specification.

The object of my invention is to provide means in a hat-forming block whereby the hat-block is especially adapted for shaping and forming bell-crowned hats made of straw braid plaited and sewed together for ladies' use. The means for accomplishing this is embodied in the novel devices or apparatus herein shown and described, which apparatus is peculiarly well adapted for convenient and ready use, as well as for obtaining successful results in the forming of hat-crowns of the bell form.

The invention consists of a hat-block, its parts, and combinations of parts, as herein described and claimed, or the equivalents thereof.

In the drawings, Figure 1 is a top plan view of my improved hat-block, the parts being in their initial positions. Fig. 2 is a top plan view of my improved hat-forming block, the parts being in the positions which they take when forced into place for shaping or forming the crown of a hat. Fig. 3 is a transverse vertical section of the hat-block, the parts being in the initial positions shown in Fig. 1. Fig. 4 is a transverse vertical section of the hat-block, the parts being in the positions shown in Fig. 2. Fig. 5 is a transverse vertical section of the hat-block at a right angle to the section shown in Fig. 3, the parts being in the initial positions shown in Fig. 1. Fig. 6 is a transverse section of the hat-block at a right angle to the section shown in Fig. 4, the parts being in the positions shown in Fig. 2; and Fig. 7 is a view of one of the movable members of the block, the view showing the bottom and beveled periphery of the member.

In the drawings, 2 is the base of the hat-block, the upper surface of which may be and advisably is so formed as to be adapted to shape the brim of a hat on the top surface

thereof, the brim resting on the surface of the base. In the drawings the top surface of this base is shown as concave, being thereby adapted to form a brim of a hat that would be more or less upturned outwardly. The 55 conformation of this hat-shaping surface is liable to be changed frequently, at least every year, to adapt it for shaping hats thereon of a new fashion in each successive year. The shape of this base is not material to the present invention, nor, in fact, is it necessary that the base should have a top surface that is adapted for the shaping of a hat-brim thereon.

In the construction of my improved hat-forming block there is a medially-disposed 65 member 3, which is fixed on some base, as advisably the base 2 of the character of the one shown in the drawings. It will be understood that this base, with the hat-forming block thereon, is portable, so that it can be placed 70 on and removed from a heater or other suitable support for the apparatus. The fixed medial member 3 has side walls that incline inwardly upwardly, giving it in the construction shown in the drawings the form of a 75 truncated pyramid, though the form of this fixed member will depend on the form given to the movable members making up the other portions of the hat-block. In the construction shown in the drawings there are two 80 movable members 4 4, which severally form portions of the rim or periphery of the block and are located severally on opposite sides of the medial member 3 and are secured thereto movably and yieldingly by an interposed 85 coiled spring 5, which passes freely transversely through the member 3 in an aperture therefor and is secured or anchored at its ends, respectively, to the members 4 4 in apertures therefor, being fastened therein 90 conveniently by pins 6 6, inserted in the members 4 4 and passing through terminal eyes or loops of the spring. The spring-aper- 95 tures in the movable members 4 4 are substantially in alinement with the spring-aper- 100 ture in the fixed medial member 3. Two other movable members 7 7 make parts of the hat-block, which members are disposed opposite each other on opposite sides of the medial member 3 and are interposed between

the members 4 4. The movable members 4 4 and 7 7 form the rim or periphery of the hat-block and when forced into and set in the positions shown in Figs. 2, 4, and 6 they form 5 the active or operating hat-forming block—that is to say, they are then in positions in which they form the shaping hat-block in its completed and set form for shaping or forming thereon the bell-crown of a hat. When 10 in the positions shown in Figs. 2, 4, and 6, the lateral exterior surfaces of the members 4 4 and 7 7 unitedly form the perimeter or side wall of the hat-forming block, adapted to form thereon a bell-crown hat of a circular or 15 slightly-oval form. It will be observed that when the members of the block are disposed as shown in Figs. 2, 4, and 6 the outer peripheral wall of the block flares outwardly, thus adapting it for shaping the bell-crown of a 20 hat. The construction of the members 3, 4, and 7 of the block is such that when they are forced into the positions shown in Figs. 2, 4, and 6 they form the complete hat-block properly set for shaping a bell-crown. It will be 25 observed that the inner walls 8 of the members 4 4 are so formed that they are in a substantially vertical position when in the completed and set block, as shown in Figs. 2 and 6, and it should be understood that the movable 30 detachable members 7 are capable of being forced upwardly from their positions between the ends of the members 4 4, as shown in Figs. 2 and 4, to those illustrated in Figs. 1, 3, and 5 and that they are thus forced upwardly by the members 4 4 when relieved of 35 a holding-down load and pulled toward each other by the spring 5, which members 4 4 are thereby tilted into the positions shown in Fig. 5, in which the exterior lateral walls of the members 4 4 are in vertical positions. 40 The members 7 7 are of wedge form in radial section, as is shown in Fig. 4. As thus formed the inner surface of each of these members rests on the side of the member 3, and as this 45 inclines inwardly upwardly these members 7 7 when they are raised from the position shown in Fig. 4 move inwardly, as well as upwardly, riding on member 3 in the manner shown in Fig. 3, whereby they also, like the members 4 4, are brought toward each 50 other to such extent that a bell-crowned hat theretofore on the set hat-block can be readily lifted therefrom. The ends 9 9 of each of these members 7 are inclined inwardly downwardly, and each end fits on a correspondingly-beveled surface of one of the members 4. By this construction the members 7 7 when forced from the position shown in Figs. 1, 3, and 5 downwardly into 55 the position shown in Figs. 2 and 4 force the members 4 4 outwardly, tilting them over into the positions shown in Figs. 2 and 6, thus setting the hat-block for hat-shaping work, and by this construction the members 60 7 7 are forced upwardly and inwardly along the member 3 under the compression wedg-

ingly of the members 4 4 under the action of spring 5 when the holding-down load is removed.

Fig. 7 shows an under side view of one of the members 4, exhibiting the flat bottom 10, the curved beveled perimeter 11, and the recess 12, within which the member 3 fits. The shoulders 13, which are at the bottom of the member 4, fit against the sides of the fixed medial member 3 and prevent the member 4 from moving endwise with reference to the medial member.

In the manufacture of a straw hat this forming-block is employed first by the operative during the sewing of the braided strip of straw to itself in the making of the crown of the hat by placing the partially-made crown over the block when in the position shown in Figs. 1, 3, and 5 and pressing down the members 7 7, with the partially-built crown of the hat thereon, into the set-block positions, shown in Figs. 2, 4, and 6, whereby the operative ascertains that the crown of the hat is of a proper size substantially to fit the block. When the crown is completed, so far as sewing the straw braid is concerned, the thus-completed crown is saturated with a liquid stiffening material and is placed on the block when in the position shown in Figs. 1, 3, and 5, and the crown and the members 7 7 are forced down, tilting and spreading the members 4 4 until the block, with the crown thereon, assumes the set form shown in Figs. 2, 4, and 6, when the crown and the block are held down by placing a weight on the top thereof, and leaving the crown to dry the weight is removed, and thereupon by the automatic acting of the spring 5 the members 4 4 are uplifted and the members 7 7 are forced upwardly into the positions shown in Figs. 1, 3, and 5, when the hat may be readily removed from the block.

In use it is common to employ sets of these blocks of about sixteen in number, and these are placed on steam-heaters or other means for heating and drying the stiffening material, and the operative places a completed saturated crown of a hat on one of these blocks and then on another and another until hats are placed on the entire set of blocks, by which time the first hat placed on a block will be dry and can be removed, so that another hat can be placed on the block from which the first hat has been removed, and the process continued by successively removing the hats from the succeeding blocks.

What I claim as my invention is—

1. A hat-forming block, comprising a medial fixed member, marginal hat-block members secured to and tiltable inwardly and outwardly on the medial member, interposed wedging marginal hat-block members fitted by an inclined surface to the medial member adapted to be moved outwardly, by being pressed down on the medial member and to tilt the tiltable marginal members outwardly

by such downward movement, and means adapted automatically to withdraw the tilt-able members inwardly and thereby to raise the wedging members when relieved from being held downwardly.

2. A hat-forming block, comprising a medial fixed member having opposite surfaces inclined inwardly upwardly, marginal mem-
bers tilttable toward and from the medial
member, means securing the tilttable mem-
bers yieldingly tiltably to the medial mem-
ber, and wedging marginal hat-block mem-
bers interposed between the tilttable members
adapted to tilt and spread apart the tilttable
members on being forced down between them
and to be moved upwardly and inwardly on
the surface of the medial member by the com-
ing together of the tilttable members.

3. In a hat-forming block, a fixed medial
member, marginal tilttable members opposite
each other bearing at their lower edges against
the medial member and adapted to tilt to-
ward and from the upper portion of the me-
dial member, and means adapted to draw the
tilttable members yieldingly toward each
other and the interposed medial member at
the top.

4. In a hat-forming block, a fixed medial
member, marginal tilttable members opposite
each other bearing at their lower edges against
the medial member and having shoulders
passing around and engaging the medial
member preventing endwise movement of
these marginal members on the medial mem-
ber, and a contracting spring holding the
marginal members yieldingly to the medial
member.

5. In a hat-forming block, a relatively fixed
medial member, marginal members bearing

opposite each other against the medial mem-
ber at the bottom and tilttable toward and
from the medial member at the top, means
adapted to draw the tops of the marginal tilt-
table members toward the medial member
yieldingly, and marginal wedging members
fitting between and in beveled ways on the
tilttable members whereby when in place in
the block on removal of a holding means the
wedging members will be lifted and moved
inwardly by the inswinging ways on the tilt-
ing members.

6. In combination in a hat-forming block,
a relatively fixed medial member, opposite
non-hinged marginal tilttable members, means
connecting the tilttable members adapted to
tilt them inwardly automatically, and detach-
able marginal members fitting wedgingly be-
tween the tilttable members and adapted to
be moved upwardly and inwardly by the
wedging action of the tilttable members when
drawn toward each other tiltably.

7. In a hat-forming block, a base, a medial
member fixed on the base, marginal hat-block
members opposite each other and bearing at
the bottom tiltably against the medial mem-
ber, means for tilting said members toward
each other, other marginal hat-block mem-
bers interposed wedgingly between the first-
mentioned marginal members and adapted to
move wedgingly on ways therefor on said
first-enumerated marginal members.

In testimony whereof I affix my signature
in presence of two witnesses.
